UNITED STATES PATENT OFFICE.

HENRY L. ALBISSEER AND JOSEPH SIMON, OF RAHWAY, NEW JERSEY.

CLOTHES-POUNDER.

1,107,009.

Specification of Letters Patent. Patented Aug. 11, 1914.

Application filed February 12, 1913. Serial No. 747,914.

To all whom it may concern:

Be it known that we, HENRY L. ALBISSEER, a citizen of the Republic of France, and JOSEPH SIMON, a citizen of the United States, and both residents of Rahway, in the county of Union and State of New Jersey, have invented a new and Improved Clothes-Pounder, of which the following is a full, clear, and exact description.

This invention relates to improvements in washing apparatus, and particularly to what is known as a clothes pounder, and has for an object to provide an improved structure which will force or propel water through the clothes being washed.

Another object of the invention is the provision of a washing device formed with a reciprocating member and a supporting and distributing hood which will hold the clothes substantially in a given position, but will allow the reciprocating member to draw a washing fluid through the clothes when the reciprocating member is moved in one direction, and force the cleaning fluid through the clothes in an opposite direction when the reciprocating member is reversed so as to cause a back and forth flowing of cleaning fluid through the clothes.

In carrying out the objects of the invention, a housing is provided formed with an open ended drum or hood designed to be placed against the clothes; a cylindrical barrel or tube, and a top therefor. In the cylindrical tube or barrel is arranged a reciprocating piston operated by a suitable handle extending upwardly through the top so that the piston may be moved back and forth freely for causing compression and a suction in the barrel or drum. A spring is provided for normally returning the piston to its uppermost position when moved therefrom so as to assist in a proper manipulation of the device and to cause a reverse movement of the piston with only a small pull upon the handle.

A practical embodiment of the invention is represented in the accompanying drawings forming a part of this specification, in which similar characters of reference indicate corresponding parts in all the views.

Figure 1 is a side elevation of an embodiment of the invention; Fig. 2 is a longitudinal vertical section on an enlarged scale through the device shown in Fig. 1, the handle being shown broken off; Fig. 3 is a bottom plan view of the structure shown

in Fig. 1; and Fig. 4 is a longitudinal vertical section through the bottom part of a slightly modified form of device from that shown in Fig. 2.

Referring to the accompanying drawings by numerals, 1 indicates a handle of any desired kind, provided preferably with threads 2 so as to be threaded into the end 3 of a tube 4. Arranged in the tube 4 is a disk 5 which normally rests against end 3 so as to act as a stop for spring 6, which spring extends for the full length of tube 4 and beyond the lower end thereof so as to co-act with the hub 7 of a spider 8. The spring 6 co-acting with hub 7 and against stop 5 will continually tend to move the piston 9 from the position shown in Fig. 2 to an elevated position, namely to a position with the piston 9 in contact with the lower end of guide 10. The guide 10 is preferably formed as an inwardly projecting tube member associated with the top or cap 11, which top or cap is provided with a plurality of apertures 12 so as to allow a free passage of air back and forth above piston 9. The piston 9 may be of any desired form so as to make a tight sliding joint with the tubular body 13, the structure shown being a pair of washers 14 and 15, a pair of clamping plates 16 and 17, and retaining nuts 18 and 19.

Connected with the lower end of the tubular body 13, is a threaded ring or sleeve 20, to which is rigidly secured in any desired manner, as for instance by soldering, a bell or hood 21 flaring outwardly at the bottom. To the bottom of the bell is connected in any suitable manner, as for instance by rivets, a spider 8 which will hold the clothes from entering the bell, but will permit the free passage of water and cleaning fluid. If desired, a wire mesh 22 (Fig. 4) could be used to prevent the passage of the clothes into bell 21. When using wire mesh 22 the same is preferably held in place by a ring 23, riveted, bolted, or otherwise rigidly connected with the bell 21. A plurality of apertures 24 are provided in the lower part of bell 21, the same being of any desired size so as to allow a proper back and forth movement of the piston.

In arranging the spring 6 in the tubular member 4 with one end resting on hub 7, the same is threaded over a guiding pin 25 which is secured to the hub 7 in any desired manner, as for instance by being threaded

thereto. Part of pin 25 is continually within tube 4 so that spring 6 is properly held in position as piston 9 reciprocates.

Having thus described our invention we claim as new and desire to secure by Letters Patent:

1. In a vacuum washer of the class described, a body, a wire mesh covering the ends of said body and having the edges overlapping part of the body, a ring fitting over said overlapping edges for clamping the wire mesh in place, means extending through said ring and part of said body for clamping the ring to said body, a piston arranged in said body, and means for reciprocating said piston.

2. In a vacuum washer of the class described, a body, a hood secured to said body, means arranged at the bottom of said hood for preventing the entrance of clothes into said hood, a piston arranged in said body, a hollow operating piston rod for said piston, said piston rod being formed with an abutment, a spring arranged in said piston rod

for raising the same, and means arranged 2 in the spring for guiding the spring.

3. In a vacuum washer of the class described, a body, a hood secured to said body, a spider secured to said hood, a piston arranged in said body, a hollow piston rod 3 for operating said piston, a handle bar operating said piston rod, a spring having one end projecting into said piston rod and engaging said handle, and the opposite end pressing against said spider, and a guiding 35 pin connected with said spider and extending into said hollow piston rod, said guiding pin being arranged interiorly of said spring.

In testimony whereof we have signed our 40 names to this specification in the presence of two subscribing witnesses.

HENRY L. ALBISSEER.
JOSEPH SIMON.
